UNITED STATES PATENT OFFICE.

GEORGE W. WHITEMAN AND RUSSELL C. PAXSON, OF PHILADELPHIA, PENNSYLVANIA.

METAL WEAR MEMBER.

Application filed March 8, 1924. Serial No. 697,912.

To all whom it may concern:

Be it known that we, GEORGE W. WHITEMAN and RUSSELL C. PAXSON, citizens of the United States, and residents of Philadelphia, Pennsylvania, have invented certain new and useful Improvements in Metal Wear Members, of which the following is a specification.

Our invention relates to the metal castings, usually of manganese or similar wear-resisting metal, or metal alloy, which are associated with rails of usual type and are employed as wear members and supports in frogs, switch parts, crossings, and the like, for taking excessive wear of the car wheels and sustaining the rails in rigid relationship, and the object of our invention is to provide a construction whereby portions of such metal castings may be readily and economically prepared to exactly fit or fill the space between the head and flange of a rail or rails to which they are connected, and to lie in proper bearing or wedging contact with the head and flange of such rail or rails. As is well known, castings of manganese and other wear-resisting metals or metal alloys are very difficult to machine and the present practice is to cast them to substantially the size of the finished structure; usually slightly over-size, and then to grind the same to the proper fit. As may be well understood, allowance for shrinkage can never be accurately determined, particularly in view of the many types and shapes of castings employed, and in the present practice of preparing these cast wear members, considerable loss has been incurred owing to errors in shrinkage allowance, and errors in grinding the structure to fit; perfect wedging fit being a requirement.

The main object of our invention is to provide an improved construction for wear metal members or castings of this type, whereby an accurate wedging fit with respect to the rails or rail sections with which they are employed and to which they are secured can be obtained by manipulation of or an operation upon the casting proper without the necessity of removing a portion of the metal by grinding or otherwise to secure the desired wedging fit; thereby avoiding the very considerable loss occasioned by misfit castings. In some instances this manipulation or operation may be employed to correct errors occurring when grinding the wear metal members to the desired wed-

ing fit, whereby portions of the same may be brought by expansion to the desired shape and dimensions; in other instances the operation may be employed to render an over-size cast structure directly available for use without any subsequent grinding or other operations of any character, designed to remove portions of the same to make the required fit, and in still other instances under-size castings may be expanded to the desired shape and dimensions.

These and other features of our invention are more fully described hereinafter; reference being had to the accompanying drawings, in which:

Figure 1, is a cross-sectional view, more or less diagrammatic, illustrating a centre frog or similar member of wear-resisting metal, associated with the rails between which it is placed and to which it is secured in wedging engagement; such rails being indicated by dotted lines.

Fig. 2, is a side elevation of sufficient of the wear-resisting member or casting shown in Fig. 1, to illustrate the construction forming the subject of our invention.

Fig. 3 is a view illustrating a wear-resisting member of other cross sectional contour secured to a single rail, which is indicated by dotted lines, and

Figs. 4 and 5, are diagrammatic views illustrating a method or manner of utilizing the improved construction forming the subject of our invention to bring wear members to the desired shape and dimensions.

The use of wear-metal members for crossings, frogs, switch parts, and the like, is very well known, and a detailed description of such practice is not thought to be necessary.

The wear-metal member of manganese or other wear-resisting alloy indicated at A, in Figure 1, is provided with lateral portions or extensions 1, designed to fit between the heads 2 and base flanges 3, of the respective rails, indicated at 4, and the present practice has been to provide these wear-metal members with solid extensions disposed in wedging engagement with the head and base flange of a rail, and held thereto by a bolt, such as indicated at 5. In such practice, the castings are made slightly over-size, and the contacting surfaces 2^a and 3^a of these extensions 1, for engagement with the head and base flange of a rail, respectively, have usually been ground to

provide the desired wedging fit; such casting being originally sufficiently over-size to permit the grinding to fit. It frequently happens, however, that these end extensions 5 shrink unduly; precluding the possibility of grinding to fit in the first instance, and it has also occurred that in the grinding operation, more metal than necessary has been removed, with the result that the very necessary and desired wedging fit between the heads and base flanges of the rails cannot be effected, and when this condition arises the casting must be discarded; incurring loss of time, labor and material.

10 By the use of our invention, however, we are enabled to operate directly upon the casting of manganese or other wear-resisting metal or alloy and bring it to size if under-size, or if cast to provide a substantial fit 20 and slightly over-size to reduce portions of the same to a dimension providing a perfect wedging fit between the head and flange of the rail or rails with which it is associated.

25 To this end the casting A is grooved longitudinally of the same as indicated at 10; the groove or grooves extending a sufficient distance into the body of the casting and being of such shape as to permit the portions flanking such groove or grooves to be pushed together under pressure to bring the rail-engaging parts, the extensions 1, for instance, to the desired wedging fit. On the other hand, if the portions of the extensions 30 are under-size, they may be spread to provide the desired wedging fit by pressure applied to the walls of the groove or grooves to displace the portions flanking the same.

35 Our invention broadly, comprises a construction which involves this side grooving of the casting longitudinally of the same, independently of the particular contour or cross sectional area of the groove.

40 In a casting such as that indicated at A, in Fig. 1, which is interposed between a pair of rails, each of the side extensions 1, fitting between the head and base flange of such rails will be grooved, while in a section such as indicated at Fig. 3, which is applied at one side only of a single rail, the groove will be disposed in the portion fitting between the head and flange of the rail.

45 In Figs. 4 and 5, we have illustrated, diagrammatically, one manner in which over-and under-size castings may be brought to the desired dimension, configuration or shape to provide a wedging fit between the head and flange of a rail.

50 In the diagram illustrated in Fig. 4, the full lines of the member A represent the size and shape of the casting as taken from the mold, with its side grooves 10, and the dotted lines at the side portions represent the shape and conformation that should be im-

parted to such side portions in order that the desired wedging fit with the head and flange of a rail may be provided. To this end the casting may be placed between die members B and C, and upon proper operation of the same, the side portions flanking the groove may be brought to the conformation indicated by the dotted lines, which agrees with the surfaces 2^a and 3^a of the wear-metal member indicated in Fig. 1. 55 This compression will, in all probability, displace a portion of the metal inwardly with respect to the grooves 10, as indicated by the dotted lines x.

60 In the diagram illustrated in Fig. 5 the casting to be operated upon is indicated as slightly under-size, and this may be brought to the normal dimension and configuration for the desired wedging fit with the rail head and flange by applying wedging means D in engagement with the walls of the grooves; the pressure so applied displacing the metal to the configuration indicated by the dotted lines 2^a and 3^a, to form the upper and lower surfaces of the portions designed for wedging engagement with the head and base flange of the rail.

65 As may be understood, the shape of the groove or grooves 10 may be anything that will permit this slight deformation of the wear member, by expansion or compression, to bring the engaging surfaces of the side portions to the proper conformation and dimension to provide the wedging fit between the head and the base flange of a rail.

70 As may be understood, our invention is not limited to any particular type of casting employed in railroad practice as a wear member and filler for crossings, frogs, switch parts and the like, but is applicable generally to these elements, and hence the particular illustration disclosed by the drawings is to be taken as illustrative of our improvements and not as representing the only use to which our improved construction is directed or may be applied. The member A, shown in the drawings, is indicated as substantially a solid casting, provided with the usual bolt holes a, but it will be understood that the casting may be recessed or cored in any approved or desired manner to conform with any special practice, without departing from our invention.

75 While we have mentioned the use of manganese castings, it will be understood that our invention is applicable to other types of tough or hard metal wear members and our claims in their broadest aspect are to be understood as covering manganese and any other wear member of hard or tough metal employed in railroad practice as a member to take and resist excessive wear.

80 We claim:

1. As a new article of manufacture, a

wear-metal member of material length having a portion fitting in tight engagement between the head and flange of a rail and deeply grooved longitudinally of the same 5 to permit expansion or compression of such rail-engaging portion.

2. As a new article of manufacture, a symmetrical wear-metal member of material length having side portions fitting in 10 tight engagement between the heads and flanges of a pair of rails and deeply grooved longitudinally of the same to permit expansion or compression of such rail-engaging portion.

3. As a new article of manufacture, a wear-metal member of material length having a portion arranged to fit between the head and flange of a rail and deeply grooved longitudinally of the same to permit 20 expansion or compression of such rail-engaging portion.

4. As a new article of manufacture, a wear-metal member of material length having portions arranged for a wedging fit 25 between the heads and flanges of rails; said portions being deeply grooved longitudinally of the same to permit expansion or compression of such rail-engaging portion.

5. The combination, with a rail, of a metal 30 wear member of material length having a portion fitting between the head and flange of the rail, with a deep groove longitudinally of the same and intermediate the engaging surfaces of said fitting portion of said wear member permitting expansion or compression thereof to permit its engaging surfaces to accurately fit between the head and flange 35 of the rail.

6. The combination, with a rail, of a metal 40 wear member of material length having a portion disposed between the head and flange of the rail, with a deep groove longitudinally of the same and intermediate the engaging surfaces of said fitting portion of 45 said wear member permitting expansion or compression thereof to permit said engaging surfaces to wedge between and accurately fit the head and flange of the rail, and means for confining said engaging portions in place.

7. The combination, with a pair of rails, 50 of a symmetrical metal wear member of material length having portions in wedging fit between the heads and flanges of said

rails, with deep grooves longitudinally of 55 the same on opposite sides and intermediate the engaging surfaces of said wear member permitting expansion or compression thereof to permit said engaging surfaces to accurately fit the heads and flanges of the 60 rails, and means for confining said wear member in place.

8. The combination, with a rail, of a metal 65 wear member of material length having a portion in wedging fit between the head and flange of the rail, with a deep channel or groove longitudinally of the same and intermediate the engaging surfaces of said 70 wear member, and means for confining said wear member in place.

9. A wear-metal members of material 75 length having a portion fitting between the head and flange of a rail; said member being deeply grooved longitudinally of the same to permit expansion or compression of said portion to effect a wedging fit with the head and flange of said rail.

10. A wear-metal member of material 80 length of symmetrical cross sectional contour having portions fitting between the heads and flanges of a pair of rails; said member being deeply grooved longitudinally of the same in each portion to permit expansion or compression of said portions 85 to effect a wedging fit with the heads and flanges of said rails.

11. A wear-metal member of material 90 length having a portion for wedging engagement between the head and flange of a rail; said member being deeply grooved 95 longitudinally of the same intermediate the engaging faces of said portion to permit expansion or compression thereof to effect an accurate wedging fit with the head and flange of said rail.

12. A wear-metal member of symmetrical 100 cross sectional contour having portions for wedging engagement between the head and flange of a rail; said member being longitudinally grooved on opposite sides intermediate the engaging faces of said portions 105 to permit expansion or compression thereof to effect an accurate wedging fit with the head and flange of said rail.

In witness whereof we have signed this 105 specification.

GEORGE W. WHITEMAN.
RUSSELL C. PAXSON.
